Primary Examiner — Mark Goodwin*(74) Attorney, Agent, or Firm* — Peter K. Zacharias; Patrick M. Sheldrake(57) **CLAIM**

The ornamental design for a roll-over protective structure for a construction machine, as shown and described.

DESCRIPTION

FIG. 1 is a perspective view of a roll-over protective structure for a construction machine showing our new design.

FIG. 2 is a front perspective view of the roll-over protective structure of FIG. 1.

FIG. 3 is a rear perspective view of the roll-over protective structure of FIG. 1.

FIG. 4 is a left-side view of the roll-over protective structure of FIG. 1.

FIG. 5 is a right-side view of the roll-over protective structure of FIG. 1.

FIG. 6 is a front view of the roll-over protective structure of FIG. 1.

FIG. 7 is a rear view of the roll-over protective structure of FIG. 1.

FIG. 8 is a top view of the roll-over protective structure of FIG. 1; and,

FIG. 9 is a bottom view of the roll-over protective structure of FIG. 1.

The dashed lines shown in FIG. 1 represent environmental subject matter and form no part of the claimed design.

The dashed lines shown in FIGS. 2-9 are for illustration only and do not form part of the claimed design.
